CLAIM

The ornamental design for an audio visual device, as shown and described.

DESCRIPTION

FIG. 1 is a perspective view of an audio visual device showing our new design;

FIG. 2 is a front elevational view thereof;

FIG. 3 is a rear elevational view thereof;

FIG. 4 is a top plan view thereof; and,

FIG. 5 is a bottom plan view thereof.

Portions in broken lines are for illustrative purposes only and form no part of claimed design. The dot-dash broken lines shown in drawings define, but are not included in, the boundaries of the claimed design.
